HAIR CURLER

Max M. Newman, New York, N. Y.

Application October 12, 1940, Serial No. 360,858

11 Claims. (Cl. 132—33)

My invention relates to hair curlers and more particularly to such devices designed to form a curl and supply a hair pin to the formed curl.

This application is a continuation-in-part and an improvement on the device described in my co-pending application Ser. No. 314,193.

As in my former application, the principal object of my invention is to simplify the procedure of producing such curls in that the necessary operations are automatically accomplished.

Another object of my invention is to eliminate the conventional clamp found in most curlers while providing automatic means for initially grasping the hair and finally releasing it.

Another object of my invention is to provide improved means for enabling the curl to be slid off the end of the mandrel around which it has been formed.

A further object of my invention is to provide a curler of such construction as to supply a hair pin to a formed curl while automatically collapsing the mandrel and releasing the grasp of the clamp, all these steps being accomplished in a more positive and efficient manner.

Finally, a most important object of this invention is to further simplify the construction so that the component parts of the device are reduced to a minimum, the construction being in fact much simpler than devices not having the operating advantages above described.

Other objects of my invention will be apparent from the following description, it being understood that the above general statements of the objects of my invention are intended to explain and not to limit it in any manner.

Fig. 1 is a top view of the device as the hair pin is supplied to the curl, the broken lines indicating the original position of the mandrel section.

Fig. 2 is a side view thereof.

Fig. 3 is a bottom view thereof, partly broken away.

Fig. 4 is a longitudinal section of the device in the normal position, i. e. before the hair pin is actuated to grasp the formed curl.

Fig. 5 is a bottom, elevational view of the handle portion of the curler.

Fig. 6 is a top view in the normal position, as distinguished from Fig. 1.

Fig. 7 is a side view thereof.

Fig. 8 is a section on the line 8—8 of Fig. 6.

Fig. 9 is a section along the line 9—9 of Fig. 6.

Fig. 10 is an enlarged fragmentary view illustrating the spreading means whereby the shanks

of the hair pin are separated prior to engagement with a formed curl.

Fig. 11 is an enlarged fragmentary view illustrating the lateral displacement of the spreader when the hair pin is ejected.

Fig. 12 is a section along the line 12—12 of Fig. 8.

In the drawing, 15 represents the upper mandrel jaw of the curler, said mandrel jaw being integral with the handle 16. The hollow handle 16 is oblong in cross-section and is provided with guide ridges 17 defining a slot 18 whose inner end is open as shown. On the handle 16 opposite the slot 18 is the closed slot 19. Secured to the inner wall of the handle 16 by the bolt 20 is the hair clamping spring jaw 21.

A member 22 of tubular resilient metal stock has one end thereof disposed within the handle 16 and is secured thereto by the pivot pin 23.

It will be observed in Fig. 12 that the member 22 is confined against movement in a direction parallel to the minor or conjugate axis of the oblong handle 16 by having its diameter substantially the same as the length of said minor axis. On the other hand, movement in a direction parallel to the major or transverse axis thereof is permitted and such movement is a result of the member 22 rocking about the pivot pin 23 in a manner to be hereinafter described. Such movement is also described as being in a direction perpendicular to the longitudinal axis of the handle 16.

The member 22 is provided with a cam slot 24 arranged to be substantially in alignment with the slot 19 of the handle 16. As shown in Fig. 9, the member 22 has a spreader 25 integral therewith and located substantially in the path of the slot 18 of the handle 16. The spreader 25 is undercut to permit it to be engaged by the shanks of a hair or "bobby" pin B. The free end of the member 22 is bifurcated and the leg 26 has its concavity filled by the member 27 soldered thereto.

The other leg 28 of the bifurcated free end of the member 22 is provided with an opening 29 and through this opening the hair clamping spring jaw 21 extends so as to be disposed between the legs 28 and 26 of the member 22.

A hair pin actuating slide 30 is provided with a projection 31 which travels in the slot 18 between the guides 17. A pin 32 is connected to the inner wall of said slide 30 and travels in the slot 19 of the handle 16 and in the cam slot 24 of the member 22. A cap 35 serves merely to enclose

the end of the device and is frictionally or otherwise secured thereto.

My invention operates in the following manner.

The slide 30 being located in the non-operating position illustrated in Fig. 7, a hair pin B is inserted in the slot 18 to embrace the spreader 25 as seen in Fig. 8. Inasmuch as the member 22 is cylindrical, it is capable of rocking movement parallel to the major or transverse axis of the oblong handle 16 and it being desirable at this time to maintain the member 22 outwardly disposed in relation to the mandrel jaw 15, a spring member 33 connected to the member 22 bears against the inner wall of the handle 16 and urges the bifurcated end of the member 22 outwardly. In order to insure the outward disposition of the member 22, a projection 34 is formed thereon (Fig. 10) and bearing as it does against the hair pin B, the member 22 is prevented from inward movement during the formation of the curl. It will be further observed in Fig. 5 that the main body of the cam slot 24 is in alignment with the slot 19 while the curved end of the slot 24 is outwardly disposed.

With the hair pin B and the slide 30 in this position, the operator applies the device to a lock of hair to be curled and the hair, guided by the clamp 21 and the leg 26 of the member 22, is received within the fork of the member 22 and clamped against the leg 26 of the member 22 by the clamp 21. The clamping action is effected by the outwardly disposed leg 26 bearing against the relatively stationary resilient clamp 21.

The device is then rotated and the lock of hair is curled around the leg 28 of the member 22, and the upper mandrel jaw 15.

At this point the slide 30 is actuated and the projection 31 urges the hair pin B along the slot 18, the spreader 25 spreading the shanks of the hair pin to permit of its subsequent return to normal position, clamping the formed curl. As the slide 30 thus travels, the pin 32 by virtue of the cam slot 24 shifts the member 22 laterally inward, against the action of the spring 33, the direction of movement being perpendicular to the longitudinal axis of the handle 16. This inward movement of the member 22 accomplishes the following results:

1. The leg 26 is urged away from the clamping jaw 21 thus releasing the formed curl.

2. The mandrel (comprising the member 22 and the upper jaw 15) is collapsed so that the device is easily withdrawn from within the formed curl.

3. The spreader 25, being integral with the member 22, is inwardly displaced allowing the hair pin B to leave the slot 17.

These results are illustrated in Figs. 3 and 4, Fig. 4 showing the leg 26 and clamp 21 in operative relation while the leg 28 and upper mandrel jaw 15 are separated. Fig. 3 conversely illustrates the separation of the clamping members, i. e. leg 26 and clamp 21, and the collapse of the mandrel members, i. e., member 22 and jaw 15.

It will be noted that this device avoids the necessity of an independent clamp for initially grasping the hair and this grasping is automatically accomplished when the device is applied to the hair. It will be further noted that the steps of collapsing the mandrel, releasing the clamp, spreading the hair pin, displacing the spreader and clamping the curl are accomplished by a single movement and that the device itself is constructed of only four essential parts, namely,

the handle and integral mandrel jaw, the member 22, the clamp 21 and the slide 30. Thus manufacture and assembly costs are reduced to a minimum while the operation of the device itself is facilitated. In the claims, and for the sake of clarity, the longitudinal mandrel elements jaw 15 and member 22 together comprise what shall be called a "mandrel."

I have shown a preferred embodiment of my invention but it is obvious that numerous changes and omissions may be made without departing from its spirit.

I claim:

1. A hair curling device comprising a handle portion, separable longitudinal elements constituting a mandrel member around which hair is adapted to be wound connected to said handle portion, a slide for supplying a hair pin to a curl wound around said mandrel member, one 15 of said longitudinal elements having a cam slot formed therein, and a pin formed on slide for urging said longitudinal element inwardly by engaging said cam slot thereby effecting the collapse of said mandrel member and facilitating 20 the withdrawal of the mandrel member from within the formed curl.

2. A hair curling device comprising a handle portion, a mandrel jaw integral with said handle portion, a bifurcated hair receiving member connected to said handle portion for inward and 30 outward movement laterally of said mandrel jaw and means to supply a hair pin to a curl of hair wound around said mandrel element and bifurcated member.

3. A hair curling device comprising a handle, a mandrel jaw connected to said handle, a bifurcated hair receiving member movably connected to said handle, means to move said bifurcated member inwardly and outwardly relative to said 40 mandrel jaw and handle, a hair clamp located within the fork of said bifurcated member and adapted to clamp a tress of hair against one leg of said fork, said hairclamp being fixedly secured to said handle whereby the inward movement of 45 said bifurcated member relative to said handle leaves said hair clamp spaced from said leg of said fork.

4. A hair curler comprising a handle, a mandrel jaw connected to said handle, a bifurcated hair receiving member pivotally connected to said handle, means to move said bifurcated member inwardly and outwardly laterally of and 50 relative to said mandrel jaw, means to support a hair pin on said handle, a slide on said handle, said slide being operative to urge said hair pin into engagement with a curl of hair on said mandrel jaw and to simultaneously bear against and cause the inward movement of said bifurcated member.

5. A hair curler comprising a handle, means to support a hair pin, a mandrel element disposed longitudinally of said handle, means to shift said mandrel element in relation to said handle in a direction substantially perpendicular to the longitudinal axis thereof, a spreader integral with said 60 mandrel element for separating the legs of said hair pin prior to engagement with a curl of hair on said mandrel element, and a slide for actuating said hair pin and for shifting said mandrel element whereby said spreader is likewise shifted and displaced so as to permit the ejection of said hair pin.

6. A hair curler comprising a handle, means to support a hair pin, a mandrel jaw connected to said handle, a bifurcated hair receiving mem-

ber pivotally connected to said handle, means to shift said bifurcated member in a direction substantially perpendicular to the longitudinal axis thereof, a hair clamp located between the fork of said bifurcated member and adapted to clamp a tress of hair against one leg of said fork, a spreader on said bifurcated member for separating the legs of said hair pin prior to engagement with a curl of hair formed around said mandrel jaw and bifurcated member, and a slide for actuating said hair pin, said slide being operative to urge said bifurcated member inwardly thereby spacing said clamp from said leg and causing the inward displacement of said spreader.

7. A hair curling device comprising a handle, a mandrel jaw connected to said handle, a bifurcated hair receiving member pivotally connected to said handle, means to shift said bifurcated member in a direction substantially perpendicular to the longitudinal axis thereof, a hair clamp fixedly connected to said handle portion and located in the fork of said bifurcated member, means to support a hair pin, a spreader on said bifurcated member for separating the legs of said hair pin prior to engagement with a curl of hair formed around said mandrel jaw and bifurcated member, and a slide on said handle portion for actuating said hair pin, said slide being operative to urge said bifurcated member inwardly thereby reducing the effective thickness of the combined curl supporting elements comprising said mandrel jaw and bifurcated member, and causing the inward displacement of said spreader to permit the ejection of the hair pin, said clamp being so disposed as to clamp a tress of hair against a leg of said fork when said bifurcated member is in the outward position whereby the inward movement thereof leaves said clamp spaced from said leg.

8. A hair curling device comprising a handle portion, a mandrel member supported by said handle portion, said mandrel member comprising upper and lower elements, a clamp connected to said handle portion and adapted to contact one of said mandrel elements to clamp a lock of hair

thereagainst whereby a curl of hair may be wound around said mandrel member, means to support and supply a hair pin to the formed curl so as to maintain its formation, and means to reduce the effective thickness of said mandrel member by causing said one mandrel element to approach the other mandrel element, the movement of said one mandrel element being relative to said clamp and being effective to cause said clamp to be spaced from said one mandrel element.

9. A hair curling device comprising a handle portion, a mandrel around which hair is adapted to be wound supported by said handle portion, a slide for actuating a hair pin so as to grasp a curl formed on said mandrel, said slide bearing against said mandrel member to cause reduction of effective thickness of said mandrel while actuating said hair pin.

10. A hair curling device comprising a handle portion, means to retain a hair pin on said handle portion, a mandrel supported by said handle portion, said mandrel being longitudinally split into jaw sections to permit of variability in the effective thickness of said mandrel, a clamp connected to said handle portion for initially clamping a strand of hair to a jaw section of said mandrel and a slide for actuating said hair pin from said handle portion to a curl of hair formed on said mandrel, said slide being operative to urge said jaw section of said mandrel inwardly thus reducing the effective thickness of said mandrel and leaving said clamp spaced from said mandrel jaw section.

11. A hair curling device comprising a handle portion, a mandrel member disposed endwise of said handle portion, a clamp secured to said handle portion for clamping a tress of hair against a section of said mandrel member, and means to shift said section of said mandrel member inwardly whereby the effective thickness of said mandrel member is reduced and whereby said clamp is caused to be spaced from said section of said mandrel member.

MAX M. NEWMAN.
